UNITED STATES PATENT OFFICE.

WILLIAM G. PHILIPS, OF NEWPORT, DELAWARE.

IMPROVEMENT IN LADDERS.

Specification forming part of Letters Patent No. 40,500, dated November 3, 1863.

To all whom it may concern:

Be it known that I, WILLIAM G. PHILIPS, of Newport, in the county of New Castle and State of Delaware, have invented a new and useful Improvement in Ladders; and I do hereby declare that the following is a full, clear, and exact description of the same, reference being had to the accompanying drawings, forming a part of this specification, in which—

Figure 1 represents a vertical transverse section of my invention when used as a step or prop ladder. Fig. 2 is a front elevation of the same when used as an extension-ladder. Fig. 3 is a transverse vertical section of the same when folded up and used as an ordinary ladder.

Similar letters of reference indicate corresponding parts in the several figures.

The object of this invention is to construct a ladder which can be used as an ordinary or as an extension ladder or as a step or prop ladder, as occasion may require.

The invention consists in curving or bending out the lower ends of the side of a ladder in such a manner that all the rounds, with the exception of the lowest one, can be made of uniform length and still the required splay of the sides of the ladder is obtained; and furthermore, if two of these ladders are hinged together, they can be readily and conveniently folded up, on account of their parallel sides, and the ladder can be used as an extension or as an ordinary ladder at pleasure.

To enable those skilled in the art to make and use my invention, I will proceed to describe it.

My ladder is constructed of two sections, A B, which are hinged together by pivots *a*. The sides *b* of the sections A B are curved out at their outer or bottom ends, as clearly shown in Fig. 2 of the drawings. The shape of the curve may either be that given to the sides of the ladder A, or it may be made in the form

given to the sides of the ladder B, the object being to obtain the required splay for the ladder. In ordinary ladders the splay is obtained by gradually increasing the length of the rounds from the top down, which causes much labor and loss of time. By curving out the sides, as above described, all the rounds, with the exception of the lowest or last one, or as many of the rounds as may be desired, can be made of uniform length, and the construction of the ladder is thereby considerably facilitated. The sides of the two sections remain parallel nearly from end to end, and the two sections can be conveniently hinged together and folded, as shown in Fig. 3, or used as an extension-ladder, as shown in Fig. 2. In the latter case pins *c*, passing through holes in both sections, render the ladder rigid.

C is a platform, which is hinged to the upper round of the section A. This platform is provided with a cleat or catch, *d*, at its under surface, and if my ladder is used as a step or prop ladder the platform is turned down to a horizontal position, causing the cleat *d* to catch over the upper round of the second section, B, of the ladder. By these means the two sections are prevented from spreading any farther than desirable, and the platform answers to set the basket on or to stand on to gather fruit.

This ladder is cheap in its construction, it is light and easily handled, and it is very convenient because it can be used in its different forms with equal facility.

What I claim as new, and desire to secure by Letters Patent, is—

Curving or bending out the sides *b* of a ladder, substantially as and for the purpose shown and described.

WM. G. PHILIPS.
